CATALYTIC CRACKING AND REFORMING
PROCESS

Harold J. Hepp, Bartlesville, Okla., assignor to
Phillips Petroleum Company, a corporation of
Delaware

Application January 23, 1948, Serial No. 4,045

2 Claims. (Cl. 196—49)

1

The present invention relates to the art of hydrocarbon conversion. In a particular modification the present invention relates to the conversion of a relatively heavier hydrocarbon and the reforming of a refractory stock for an improved yield of gasoline. In one specific aspect the present invention relates to catalytic reforming of naphtha in the presence of refractory heavier hydrocarbon stock and to the concomitant catalytic conversion of gas oil and further improvement of the reformed naphtha in the production of an improved gasoline.

Many cracking methods are known and a wide range of cracking conditions has been disclosed. It has been desirable to improve the quality of gasoline produced and it has been found that relatively specific conditions are usually best suited to different and particular feed stocks, that is, a particular feed stock of relatively narrow range responds most effectively to a particular set of conditions of temperature and pressure of fairly narrow range with certain particular catalytic agents. It has also been found that two or more of the particular feed stocks may be combined in conversion processes such as cracking, and slightly different conditions of processing applied thereto to prepare satisfactory gasoline. It has also been proposed to convert hydrocarbon stocks of various boiling ranges with subsequent separation and further treatment of individual fractions thereof. Thus, in at least one instance it has been proposed to treat a relatively light hydrocarbon stock free of heavier materials and subsequently to add a heavier hydrocarbon stock to a resulting effluent with further treatment of the mixture under more drastic conversion conditions in the production of motor fuels.

I have now found that an improved gasoline may be prepared in increased yields by a process which comprises treating a mixture of relatively light and relatively heavy refractory hydrocarbon stocks under conditions suitable for reforming the light hydrocarbons, adding relatively mutable heavy hydrocarbons to the effluent from this treatment, and further treating the second mixture under milder conversion conditions. In general, comparable hydrocarbon oils from different sources or following various treatments show different properties; thus, virgin gas oil from untreated oils is usually more easily converted, or mutable, than comparable gas oil from the product of a catalytic treatment of hydrocarbon oil. Broadly speaking then, the present invention comprises reforming a mixture of

naphtha and a refractory heavy hydrocarbon stock, such as recycle catalytic gas oil, under fairly drastic conditions of conversion and without separation of the resulting reformed effluent, adding virgin gas oil and treating the latter mixture under conditions suitable for cracking the gas oil while the reformed naphtha and heavier stock are further improved and transformed concomitantly with the conversion of the gas oil.

10. It is, therefore, the object of the present invention to provide a process of preparing increased yields of improved octane number gasoline. A further object is to provide a process of increasing the yield of an improved gasoline from a mixture of gas oil and reformed naphtha. Another object is to provide a novel process of reforming a mixture of naphtha and heavier hydrocarbons and of concomitantly cracking a gas oil and a reformed naphtha to produce increased yields of improved gasoline. A further object is to provide a novel process of preparing improved gasoline by reforming and cracking a mixture of naphtha and refractory oil and subsequently upgrading and cracking the reformed naphtha and a mutable heavier oil. Other objects will be apparent to those skilled in the art from the accompanying discussion and drawing.

15. The accompanying figure is a diagrammatic view in elevation illustrating one modification 30. of the present invention.

20. By the process of this invention a virgin cracking stock such as gas oil, a relatively refractory recycle hydrocarbon stock and a naphtha may be cracked and reformed. Thus, a relatively 35. heavy refractory hydrocarbon stock may be cracked during the reforming of a naphtha and an upgrading of the products economically effected during a subsequent cracking of an intermediate heavy stock such as a virgin gas oil. 40. The process is performed in a single, integrated unit with substantial savings in equipment and operational cost. More specifically, a recycle catalytic stock may be cracked and a naphtha stock reformed concurrently in a first catalyst 45. chamber under relatively severe conditions since these two operations are suitably carried out under substantially the same conditions with the same catalyst. Further improvement of the reformed naphtha and the gasoline obtained from 50. cracking the recycle stock is realized by subsequent treatment under somewhat milder conditions which are especially well suited to cracking of a virgin cracking stock, such as virgin gas oil. Thus, the effluent of the recycle cracking and 55. naphtha reforming is combined with a virgin

cracking stock and simultaneously processed in a second catalyst chamber under the milder processing conditions which will upgrade the products from the first catalyst chamber and promote cracking of the virgin stock for the production of a further quantity of gasoline.

In addition to the realization of conversions and transformations occurring the various hydrocarbon stock characterized by particular properties and boiling ranges is the very important feature of having a lighter hydrocarbon present during the conversion of a heavier hydrocarbon. It is found that much more complete conversion of any particular heavier stock to products in the gasoline range is possible with less formation of undesirable carbonaceous deposits and gases when relatively lighter hydrocarbons are present during the conversion. These lighter compounds which comprise especially the normally liquid hydrocarbons of low end point are reformed and converted into valuable product themselves while providing favorable diluent and other beneficial conditions during the conversion of the heavier compounds.

It is to be appreciated that cracking and reforming are affected by both contact time and temperature and that the milder conditions referred to in the second catalyst chamber will be interpreted as meaning a combination of various specific conditions to give a milder treatment to the materials in the second chamber. Thus, milder conditions in the second chamber may be understood to mean those conditions of contact time, temperature, and pressure which would produce less conversion of a given charge stock than is produced under conditions prevailing in the first catalyst chamber. Hence, the milder conditions of the second chamber may be due to a lower temperature or a lower contact time, or to both. Although it is possible that the temperature of the second chamber could be higher than the temperature of the first chamber and the contact time of the charge shortened sufficiently that the results would be a milder conversion, it is preferred that the temperature in the second chamber be at least somewhat lower than the temperature in the first chamber. Thus, a preferred condition in the first catalyst chamber may be a temperature between about 900 and 1100° F. and a superatmospheric pressure between about atmospheric and 300 pounds per square inch and a time sufficient to reform the naphtha and to convert the heavier hydrocarbons to substantial amounts of gasoline. Conditions in the second catalyst chamber after the addition of gas oil to the products from the first catalyst chamber will preferably be milder than those in the first chamber, but suitable to crack and convert the gas oil to desirable products in the gasoline range and to upgrade the products from the first conversion zone.

Referring to the drawing, a hydrocarbon such as naphtha boiling between about 200 and about 400° F. is introduced by a line 10 into a heating zone 11 and thence through line 12 into a first catalyst chamber 13. Relatively heavy hydrocarbons are introduced through a recycle line 14 and/or through a line 15 into admixture with the naphtha charged. Where desirable, lighter hydrocarbons may also be added to the naphtha charge through a line 17 and may consist in part or entirely of recycle C₃ and C₄ hydrocarbons from a subsequent separation step, returned through a line 18. The heated hydrocarbon mixture passes through catalyst chamber 13 where the

naphtha is reformed and the recycle and/or heavy stock is cracked into substantial yields of gasoline. An inert diluent such as steam may be introduced through a line 20, heated to a desirable temperature in a heater 21 and introduced into the catalyst chamber with the hydrocarbons through a line 22. Additional steam may be added at various points throughout the catalyst chamber through a line 26 and manifold lines 23, 24 and 25 as required to supply additional heat to the conversion at various points and to serve as a diluent in the conversion zone. The product effluent from chamber 13 is withdrawn and conducted through a line 27 into a second catalyst chamber 28. A virgin cracking stock, such as a gas oil, is introduced through a line 30, heated to a temperature between about 800 and 1050° F. in heater 31 and added to the product effluent entering chamber 28. As desired, steam may be added to the gas oil through a line 33 before the heater or through a line 34 immediately before the second catalytic reactor, or at both places. Gaseous hydrocarbons may also be mixed with gas oil through a line 35 as required. The heated gas oil and products from the first catalyst chamber are mixed as described and introduced into the second catalyst chamber 28 where the gas oil is cracked and the products of the first catalyst chamber are upgraded at a temperature between about 800 and 1050° F. and a pressure between about atmospheric and 250 pounds per square inch. The cracked and upgraded products from the second catalyst chamber are withdrawn through a heat exchanger 37 in a line 38 into a fractionating zone 40 which may represent several individual fractionators necessary to make the separation desired. Heat may be supplied thereto by steam coils, reboilers or other customary means (not shown). From the system, C₂ and lighter gases are removed through a line 41. Normally gaseous products such as the C₃ and C₄ hydrocarbons are removed by a line 42 or may be recycled to the catalyst zones by a line 18 as described above, and a gasoline fraction is recovered by a line 43 and taken to storage or further treatment (not shown). A heavy residue is removed from the fractionating zone by a line 44, and an intermediate hydrocarbon fraction heavier than gasoline is recovered through a line 45 and may be recycled to the first catalyst chamber 13 through line 14 as the relatively refractory hydrocarbon to the first conversion zone as described. Various valves, pumps, and other equipment necessary to practice the process will be obvious to one skilled in the art and have been omitted from the discussion and drawing for the sake of clarity. In the conversion of hydrocarbons by the present method, a suitable charge to the first catalyst chamber may be a hydrocarbon mixture comprising 50-70 volume per cent of a naphtha boiling between about 200 and 400° F., 5-15 volume per cent C₃ and C₄ gases, and the remaining 15-45 volume per cent substantially heavier hydrocarbons. The catalyst may be cracking and reforming catalysts of high, or relatively high, catalytic activity operating at a temperature between about 900-1100° F. at a pressure between about atmospheric and 300 pounds per square inch. Generally the space velocity will be between 1 to 5 liquid volumes of charge per volume of catalyst per hour based on the total hydrocarbon charge and, if desired, steam may be added at 10 to 30 pounds per barrel of liquid charge. Conditions in the second catalyst cham-

ber are controlled such that a milder conversion is effected as described. In this latter chamber catalyst of lower activity may be used and a lower temperature between about 800-1025° F. and pressure between atmospheric and 250 pounds per square inch employed. Preheated gas oil is added at the rate of about 0.5-5 liquid volumes of the gas oil per volume of catalyst is delivered per hour. Similarly, additional steam may be added in this conversion zone, if desirable. The specific set of conditions in each conversion zone will, of course, depend upon the particular charge stock being treated and the catalyst employed in each zone. The conditions stated merely set out an optimum range, and the most satisfactory combination is readily determinable for any particular charge.

The contact catalysts suitable for the present process are those having activity in promoting the cracking of gas oil and the reforming of naphtha and are particularly those rugged minerals or natural and synthetic mixtures thereof and similar materials comprising bauxite, brucite, various clay-type minerals and active aluminum silicates. These natural catalysts may be used after activation by various means such as acid treating and/or may be promoted with minor amounts of active metals or metal salts or oxides. Also useful are natural materials comprising zirconia, titania, and synthetic preparations comprising zirconia, titania, magnesia, alumina, and various silica-alumina combinations. These latter materials may be promoted with minor quantities of metal oxides, particularly those of chromium, nickel and zinc.

After periods of service in our process, these catalysts are gradually deactivated through accumulation of tarry deposits and carbonaceous residues. When their activity has declined to a degree which renders the conversion unsatisfactory, they are quickly and completely restored to substantially their original activity by reactivation at controlled temperatures in an oxidizing atmosphere. For this reactivation, it is usually preferred to pass oxygen-containing gases, such as mixtures of air with steam, nitrogen, carbon-dioxide or inert combustion gas, through the catalyst to burn off the materials responsible for deactivation without thereby producing combustion temperatures harmful to the catalyst. By providing a plurality of catalyst chambers, it is possible to operate continuously, with one or more chambers on stream while spent catalyst in other chambers is being reactivated.

In a typical example of the present invention a 35° A. P. I. catalytic gas oil distilling between about 480 and 680° F. is admixed with an equal volume of 33 octane number naphtha of 440° F. end-point. The mixture is vaporized and charged, together with 60 pounds of steam per barrel of liquid charge, at a pressure of 85 pounds per square inch gage and 1025° F. to a catalyst chamber containing bauxite at a rate of 1.5 barrels of liquid hydrocarbon per hour per barrel of bauxite. Under these conditions, the naphtha is reformed to yield about 80 per cent of a 55 octane number gasoline and the gas oil is cracked to yield about 27 per cent of 77 octane number gasoline. To the effluent from this first chamber is added preheated virgin gas oil and steam, and the combined stream is passed through a second catalyst chamber at a temperature of 1000° F. and a space velocity of 1.5 barrels of hydrocarbon per hour per barrel of bauxite. In the second chamber the virgin gas oil is cracked to yield about 35 per cent of 77 octane number gasoline.

In addition further cracking of the catalytic gas oil and additional reforming of the naphtha occur. Also light olefins formed in the first step are partly converted to gasoline in this second chamber. Gasoline is recovered in a larger yield and has a higher octane number than the gasoline which is recovered from separately treating the individual stocks and combining the gasoline produced during the separate treatments.

10 Various changes and modifications may be made without departing from the spirit of the invention and will be apparent to those familiar with the art. The example is illustrative only and is not to be interpreted as limiting the scope of the disclosure and claims which are intended to cover all aspects of the invention inherent with the disclosure.

I claim:

1. An improved process for the manufacture of motor fuels which comprises treating an admixture of hydrocarbons comprising 50 to 70 volume per cent of naphtha, 5 to 15 volume per cent of added C₃ and C₄ gases and 15 to 45 per cent of refractory gas oil in a first catalytic zone at a temperature between about 900° and 1100° F. and at a pressure between about atmospheric and 300 pounds per square inch and at a space velocity between 1 to 5 volumes of total hydrocarbon charge per volume of catalyst per hour to substantially reform the said naphtha and crack the said refractory gas oil, withdrawing a resulting reformed effluent, admixing sufficient virgin gas oil with all of said reformed effluent to permit a space velocity between about 0.5 to 5 liquid volumes of said virgin gas oil per volume of catalyst per hour in a second catalytic zone, contacting the thus resulting mixture with a cracking catalyst in said second catalytic zone at a temperature between about 800° and 1050° F. and at a pressure between about atmospheric and 250 pounds per square inch and separately recovering a gasoline fraction and an intermediate hydrocarbon fraction from the resulting product effluent from said second catalytic zone.

2. An improved process for the manufacture of motor fuels which comprises treating an admixture of hydrocarbons comprising substantially equal volumes of a refractory gas oil and a naphtha in a first catalytic zone at a temperature of about 1025° F. and at a pressure of about 85 pounds per square inch thereby substantially reforming the said naphtha and cracking the said refractory gas oil to yield substantial quantities of a low octane gasoline; withdrawing a resulting reformed effluent, admixing a substantial quantity of virgin gas oil with said reformed effluent; contacting the thus resulting mixture with a cracking catalyst in a second catalytic zone at a temperature of about 1000° F. to substantially crack said virgin gas oil and to improve the octane number of the said low octane gasoline produced in said first catalytic zone; and separately recovering a gasoline fraction and an intermediate hydrocarbon fraction from the resulting product effluent from said second catalytic zone.
